UNITED STATES PATENT OFFICE.

JOHN J. NEARY, OF DOUGLAS, ARIZONA.

SHOE-FASTENER.

1,053,529.

Specification of Letters Patent. Patented Feb. 18, 1913.

Application filed December 7, 1911. Serial No. 634,411.

To all whom it may concern:

Be it known that I, JOHN J. NEARY, a citizen of the United States, residing at Douglas, in the county of Cochise and State 5 of Arizona, have invented certain new and useful Improvements in Shoe-Fasteners, of which the following is a specification.

This invention relates to lacing studs and has for its object the provision of a comparatively simple and thoroughly efficient device 10 of this character, capable of being readily attached to the upper of a shoe, and which will not only facilitate lacing and unlacing the shoe, but also present a smooth bearing 15 surface to the cuffs of the trousers so as to prevent raveling or otherwise cutting the trousers when walking.

A further object of the invention is to provide a lacing stud including co-acting 20 clamping jaws bent to produce an intermediate guiding loop for the reception of a lacing string, there being attaching spurs formed on the jaws and extending in opposite directions through the material constituting the upper for retaining the studs in 25 position on said upper.

A still further object of the invention is generally to improve this class of devices so as to increase their utility, durability and 30 efficiency, as well as to reduce the cost of manufacture.

Further objects and advantages will appear in the following description, it being understood that various changes in form, 35 proportions and minor details of construction may be resorted to within the scope of the appended claims.

For a full understanding of the invention and the merits thereof, reference is to be 40 had to the following description and accompanying drawing, in which:

Figure 1 is a perspective view of a shoe provided with lacing studs constructed in accordance with the present invention; Fig. 45 2 is a perspective view of one of the studs detached; Fig. 3 is a plan view of one of the studs before being bent into shape; Fig. 4 is a transverse sectional view taken on the line 4—4 of Fig. 1 and looking in the direction of the arrow; Fig. 5 is a longitudinal 50 sectional view, showing the stud in position on the upper of the shoe and ready to be clenched or permanently attached thereto; Fig. 6 is a front elevation of the stud, showing 55 the position of the anchoring spurs be-

fore the stud is applied to the upper of a shoe.

Corresponding and like parts are referred to in the following description and indicated in all the views of the drawing by the 60 same reference characters.

The improved stud forming the subject matter of the present invention is principally designed for use in connection with lace shoes, and by way of illustration is 65 shown applied to a shoe of the ordinary construction, in which 5 designates the vamp, 6 the upper, and 7 the tongue receiving opening.

The fasteners are each preferably stamped 70 or otherwise formed from a single sheet of metal having its intermediate portion reduced at 8 and bent upon itself to form co-acting clamping jaws 9 and 10, one of which is flat and provided with a perforation 11 and the other concavo-convex in cross section to produce a smooth substantially spherical head 12 so as to prevent cutting or raveling the cuffs of the trousers 75 when walking. The reduced portions 8 of 80 the studs project inwardly from the opposite longitudinal edges of the upper at the closure 7 to form guiding loops 13 adapted to receive a lacing string or cord 14, the inner ends of the loops 13 being preferably 85 transversely curved to facilitate passing the lacing string 14 through said loops and also to assist in preventing abrasion of the string incident to lacing or unlacing the shoe.

The material constituting the concavo-convex head 12 of each stud is formed with spaced incisions 15 and the metal between said incisions pressed laterally between the jaws 9 and 10 to form an anchoring lug 95 16 adapted to pierce the material constituting the upper and thence pass through the perforation 11 in the flat jaw 9 so as to firmly anchor the stud in position on the upper. Extending laterally from the head 100 12 on opposite sides of the anchoring lug, are spurs 17 also adapted to pierce the upper, there being a single spur or lug 18 formed on the end of the flat jaw 9 and preferably disposed at a point between the incisions 15 so as to enter the space between 105 said incisions when the jaws are clamped in engagement with the upper. It will here be noted that the lug 18 is disposed slightly in advance of the lug 16 so that when the jaws are compressed in the act of fastening, 110

the stud on the upper, the free end of the lug 16 will extend through the perforation 11, while the free end of the lug 18 will enter the recess 19 in the head 12, formed by the incisions 15.

In attaching the studs to the upper of a shoe, said studs are positioned on the upper, preferably in transverse alinement with each other and with the jaws 9 and 10 of 10 the studs embracing the adjacent longitudinal edges of said upper. The jaws are then compressed with a suitable tool, which causes the spurs 17 and lug 18 to pierce the material constituting the upper and the free end of 15 the lug 16 to pass through the perforation 11 and in which position, it may be bent or clenched laterally into engagement with the adjacent flat face of the jaw 9, as best shown in Fig. 4 of the drawing. The opposite 20 ends of the shoe string or lace 14 are then threaded alternately from right to left through the guiding loops 13, as best shown in Fig. 1 of the drawing. Thus it will be seen that by exerting a longitudinal pull 25 on the shoe string or lace at the vamp 5, sufficient slack in the string will be produced to permit expansion of the edges of the upper at the tongue receiving opening when removing the shoe, and by exerting a 30 longitudinal pull on the ends of the shoe lace, the edges of the upper may be drawn together, thus to cause the shoe snugly to fit the foot of the wearer.

Attention is here called to the fact that 35 the inner faces of the jaws 9 are perfectly flat so as not to cause discomfort to the wearer, while the outer faces of the heads 12 of the studs are entirely devoid of surface projections so that liability of cutting 40 or raveling the cuffs of the trousers is reduced to a minimum.

While the studs are principally designed for attachment to the uppers of boots, shoes and other foot wear, it will of course be

understood that said studs may be used with 45 equally good results for lacing leggings, corsets, gloves or wherever a lacing stud of this character is found desirable or applicable.

Having thus described the invention, what 50 is claimed as new is:

1. A lacing stud formed of a single piece of metal bent upon itself to produce coacting normally separated jaws connected by a guiding loop, one of said jaws being flat, 55 a lug formed integral with said jaw and disposed at its edge portion, the other of said jaws being concavo-convex in cross section, said jaw being recessed at its edge to receive the lug of the flat jaw, the metal removed to 60 form said recess being bent to form a lug which is disposed toward the other jaw and which extends within an aperture formed in said jaw, the concavo-convex jaw being provided with prongs which together with the 65 lugs of both jaws extend through the material to which the device is secured, said prongs being bent to engage the edge portion of the flat head.

2. A lacing stud comprising coacting jaws 70 connected by a reduced intermediate guiding loop, one of said jaws being formed with a lug adjacent its outer edge, the other of said jaws being recessed to receive said lug, a lug carried by the recessed jaw, said lug 75 being disposed to enter an aperture formed in the other jaw, its terminal being bent to lie flush with the outer face of said jaw, and prongs carried by the recessed jaw, said prongs being disposed in spaced relation and arranged to be bent upon the edge of the other jaw.

In testimony whereof I affix my signature in presence of two witnesses.

JOHN J. NEARY. [L.S.]
